UNITED STATES PATENT OFFICE.

EDWARD A. LAUTEN, OF MOUNT VERNON, ASSIGNOR TO ALBERT WITTNAUER, OF NEW YORK, N. Y.

TRAVELER'S WATCH-CASE.

SPECIFICATION forming part of Letters Patent No. 449,370, dated March 31, 1891.

Application filed November 4, 1890. Serial No. 370,262. (No model.)

To all whom it may concern:

Be it known that I, EDWARD A. LAUTEN, of Mount Vernon, in the county of Westchester and State of New York, a citizen of the United States, have invented certain new and useful Improvements in Travelers' Watch-Cases, of which the following is a specification.

This invention relates to improvements in leather, pasteboard, cloth, or analogous cases that are used for holding watches in such a manner that they cannot be injured by the jolting and jarring of the car or other vehicle while traveling, or by being packed in trunks, satchels, or other packages that are handled roughly.

The object of my invention is to provide a case of this kind in which the watch can readily be placed or removed therefrom, said case being so constructed that the dial of the watch is clearly displayed when the watch is to be used, and when the watch is not in use it is held firmly and securely in the case.

The invention consists in a watch-holding case composed of two hinged sections, to one of which sections a watch-receiving pocket is hinged.

The invention also consists in the construction and combination of parts and details, as will be fully described hereinafter, and finally be pointed out in the claims.

In the accompanying drawings, Figure 1 is an elevation of my improved case for travelers' watches, the same being open. Fig. 2 is a horizontal sectional view on the line 2 2, Fig. 3, showing the case open and the watch-holding pocket swung outward. Fig. 3 is a vertical transverse sectional view through the same, the case being closed.

Similar letters of reference indicate corresponding parts.

The case is composed of two sections A and B, hinged to each other, the section B being provided with a suitable handle or carrying strap C. The section B is provided with a snap-hook B', adapted to engage a catch A' on the section A. To the inner surface of the sides of the section B the filling-pieces D are secured, and between the same the watch-holding pocket E fits, the thickness of which

is equal to the space between the inner surface of the sections A and B when closed. Said watch-holding pocket E is hinged along the central line of one side to the outer edge of one of the filling-pieces D, as shown in Fig. 2, and is thus adapted to swing into the section B and between the filling-pieces D. Said pocket E is provided in its front with a circular aperture F, of the size of the dial of the watch, so that when the watch is placed into the pocket the dial will show through said aperture. The back of the pocket is provided in its top edge with a notch G for receiving the folded-down bow a of the watch b. The inner surface of the section B is provided with a notch H for receiving part of the bow when the same is turned down and the watch is in the pocket, as shown in Fig. 3. To prevent the watch from moving up and down in the pocket a cushion or stop K is secured to the top of the section B on the inside, against which the crown d of the watch can rest, the bottom part of the watch resting on the rounded bottom of the recess formed in said pocket E. On the inner surface of the section A a padded protuberance J is formed, which, when the case is closed, passes through the opening F in the pocket E and rests on the face of the watch-dial. The watch, when held in the case, cannot shift or move in any direction, and cannot be damaged or injured by jars, etc., received while being carried in the train, railway-car, or other vehicle. When the traveler arrives at his destination and wishes to use the watch, all that is necessary is to open the case, when the dial of the watch will be fully exposed to view.

Having thus described my invention, I claim as new and desire to secure by Letters Patent—

1. The combination, with a case formed of two hinged sections, of a watch-holding pocket hinged along the center of one of its sides to the outer side edge of one of the sections and adapted to be swung in and out of said section, which watch-holding pocket is provided with an aperture through which the dial of the watch is visible.

2. The combination, with a case formed of

two hinged sections, of a watch-holding pocket
hinged at one side to one side of one section,
and a cushion or stop for the crown secured
to the top of the interior of that section to
5 which the watch-holding pocket is hinged,
substantially as set forth.

In testimony that I claim the foregoing as

my invention I have signed my name in pres-
ence of two subscribing witnesses.

EDWARD A. LAUTEN.
